UNITED STATES PATENT OFFICE.

ELVAH O. BULMAN, OF GRAND RAPIDS, MICHIGAN.

BAG HOLDER.

1,422,659.

Specification of Letters Patent. Patented July 11, 1922.

Application filed February 28, 1921. Serial No. 448,714.

To all whom it may concern:

Be it known that I, ELVAH O. BULMAN, a citizen of the United States of America, residing at Grand Rapids, in the county of 5 Kent and State of Michigan, have invented certain new and useful Improvements in Bag Holders; and I do hereby declare the following to be a full, clear, and exact description of the invention, such as will enable others skilled in the art to which it 10 appertains to make and use the same.

This invention relates to bag holders. It is particularly concerned not only in a new and useful construction for use in holding a 15 quantity of bags together and in an upright position whereby individual bags may be readily removed at will when needed, but is also directed to a support for the individual holders for bags which is of practically 20 universal adaptation for the positioning of the bags where ever desired, either suspended over the counter, resting on the counter or floor, or fixed against the wall or other vertical support, the support for the individual 25 bag holders readily being available for all of these adaptations. It is the object and purpose of the present invention, primarily, to make a construction of support for bag 30 holders which attains these ends and in a simple and practical manner. A further object of the invention is to make a construction of this character at low cost so that the same may be manufactured and marketed 35 economically, yet substantially any type of installation of bag holding support furnished thereby. Many other objects and purposes than those specifically enumerated 40 will appear as understanding of the invention is had from the following description, taken in connection with the accompanying drawings, in which,

Fig. 1 is a perspective view of the bag holder of my invention showing the same suspended from above.

Fig. 2 is a front elevation thereof showing the same affixed to a base for placing on a floor or the like.

Figs. 3 and 4 are perspective views of the two main members of the support showing 45 the same separated, either one of which may be secured against a wall or other stationary vertical support.

Fig. 5 is a perspective view of one of the individual holders for bags.

Fig. 6 is a fragmentary front elevation of 55 one leg of one of said holders showing the connection of the bag retaining bail there-of, and

Fig. 7 is a section taken on the line 7—7, of Fig. 6 and looking against the edge of the 60 leg of the bag holder.

Like reference characters refer to like parts in the different figures of the drawings.

In the construction, a bar of flat metal is 65 used for one side of the support, having a vertical portion 1 which at its lower end is bent at right angles to make a foot piece 2. At its upper part it is bent outwardly and upwardly at an angle to the vertical as indicated at 3, terminating in an out-turned horizontal part 4 as shown. A second bar of flat metal of identical construction having a vertical portion 5, foot piece 6 thereon, angularly disposed portion 7 and horizontal 70 terminal part 8 is used with the first bar, the same being placed with the vertical portions 1 and 5 against each other, parts 3 and 7 forming a V. From each of the parts 3 and 7 tongues 9 are struck in spaced apart 75 relation, on which the individual holders for bags are adapted to be hung. Bolts 10 are used and passed through the portions 1 and 5 to detachably secure the bars together. A bar 11 of the same or similar stock bridges 80 the space between the horizontal parts 4 and 8 and is detachably secured thereto by bolts as shown. This bar at both ends is formed with an upturned part 12 in which a hole 12^a is made. 85

The holders for bags which are to be hung on the tongues 9 are each formed from flat metal and bent into U-shape with parallel legs 13 connected at their upper ends by an integral curved section 14. Each leg 13 at 95 its lower end is bent at right angles to make a base 15 on which the lower ends of bags are to rest, and then turned upward forming retaining members 16. The part 14 has a slot of the form shown at 17 in Fig. 5 cut 100 therethrough for the passage of a tongue 9 therethrough. This slot may also have an auxiliary recess made contiguous therewith at its upper part for use should it ever be

desirable to hang the holder on a nail, screw or the like.

A bail 18 of wire or bent from a rod is pivotally mounted on the legs of each holder.

- 5 Each leg 13 is slit vertically at two places, the metal between the outer edge of each leg and the first slit being pressed to the rear forming a socket 19, that between the two slits in the opposite direction making a co-
10 operating socket 20, while that between the second slit and the inner edge of each leg is left in the same plane with the main body of the leg as indicated at 21. The ends of the bail pass over the socket 19 and under
15 that at 20, parts 21 furnishing stops to limit the insertion of the ends of the bail as is evident.

A construction like that described may be suspended over the counter in a store, suspending cables 22 being attached through holes 12^a at their lower ends and connected to any suitable overhead support, as shown in Fig. 1. Or, if desired, the foot members 2 and 6 may be secured to a base 23 and the
20 structure be placed on the floor. Again, the bolts 10 may be removed and bar 11 disconnected, and each half secured against the wall, suitable securing means therefor passing through the openings through which
25 bolts 10 normally pass. The individual holders are readily disconnected and any of them may be placed upright on a counter and secured by fastening means passing through the openings shown in the bases 15
30 of the holder. In fact, practically any desired way of using the bag holder may be accomplished, and in one structure, all of the usual and well known ways of installing a bag holding structure may be accomplished,
35 obviating the necessity of having many different types and kinds of bag holding devices, some for suspension, some supported on the floor, and some for wall attachment.

This invention is simple, practical and efficient. With it a multiplicity of types and designs are obviated. The claims define the invention and I consider myself entitled to all forms of structure coming within their scope.

50 I claim:

1. In combination, a support comprising two bars located against each other and formed at their lower ends with oppositely located out-turned foot portions and at their
55 upper ends with portions bent outwardly and upwardly at an angle to the vertical and away from each other, each of said last mentioned portions terminating in horizontal end parts, and each being formed in its length with a plurality of spaced apart outwardly struck tongues; bolts passing through the two bars to detachably connect the same together, a horizontal bar formed at its ends with outwardly and upwardly turned
60 portions connected detachably to the upper
65 portions of the first bars, and bag holders de-

tails of the first bars, and bag holders detachably suspended one from each tongue, substantially as described.

2. In combination, a bag holding support comprising a flat bar adapted to be disposed vertically and formed at its lower end with a foot portion turned at right angles to the bar and at its upper part with a portion bent to extend upwardly at an angle to the vertical, said last mentioned portion having a plurality of tongues struck therefrom in spaced apart relation for detachably supporting bag holders, substantially as described. 70
75

3. In combination, the elements defined in combination in claim 1 and a base connected to and below the foot portions of said bars, substantially as described. 80

4. A support for bag holders comprising two identical flat bars having intermediate portions adapted to be placed against each other and detachably connected together, each at its lower end being formed with an out-turned foot portion, and at its upper end with an integral part extending upwardly and at an angle to the vertical, each of said parts being formed with spaced apart outwardly struck tongues on which bag holders are adapted to be detachably hung, and a horizontal bar detachably connecting the upper ends of said angularly disposed portions and bridging the space between them, substantially as described. 85
90
95

5. A support for bag holders comprising a bar of flat metal having a portion adapted to be positioned vertically, and a second portion extending from the first portion at its upper end forwardly at an angle to the vertical, said second portion being provided with a plurality of spaced apart bag holder carrying tongues, substantially as described. 100
105

6. A bag holder comprising a bar of flat metal bent into U-shape, the metal being bent in the direction of the width of the bar so that the legs and bend between them lie in the same plane, each leg at its lower end having a portion bent forwardly for a distance and then upwardly at right angles for a short distance, and a bail pivotally mounted at its ends on the legs above the lower ends thereof, substantially as described. 110
115

7. A bag holder comprising a bar of flat metal bent into U-shape with the sides of the legs thereof lying in the same plane, the lower ends of said legs being bent forward at right angles for a short distance and thence upwardly for a short distance, each of said legs between its upper and lower ends being vertically slotted at two places, the metal between the outer edge of each leg and the adjacent slit being pressed in one direction to form a socket, and the metal between the slits being bent in the opposite direction to form a cooperating socket, and a 120
125
130

bail having its ends received in the sockets formed on said legs to thereby pivotally mount the bail, substantially as and for the purposes described.

5 8. A support for bag holders comprising a vertically located bar having an extension at its upper end bent forwardly and extend-

ing upwardly at an angle to the vertical, and a plurality of devices on said extension located in spaced apart relation from which 10 holders for bags may be hung, substantially as described.

In testimony whereof I affix my signature.
ELVAH O. BULMAN.
